UNITED STATES PATENT OFFICE.

JOHN WESLEY DAVIS, OF CLINTON, INDIANA.

ADJUSTABLE FASTENER FOR GRAIN-CAR DOORS.

SPECIFICATION forming part of Letters Patent No. 747,150, dated December 15, 1903.

Application filed July 7, 1903. Serial No. 164,582. (No model.)

To all whom it may concern:

Be it known that I, JOHN WESLEY DAVIS, a citizen of the United States, residing at Clinton, in the county of Vermilion and State of Indiana, have invented a new and useful Adjustable Fastener for Grain-Car Doors, of which the following is a specification.

This invention relates to fasteners for the doors of grain-cars, and has for its object to simplify and improve devices employed for this purpose and to produce a door-fastening which may be readily applied to any construction of door or car and which will be cheap and simple in construction, easily operated, and which will not be liable to become disarranged while in use.

The invention consists in certain novel features of construction, as hereinafter shown and described, and specified in the claims.

20 In the drawings illustrative of the invention, in which corresponding parts are denoted by like designating characters, Figure 1 is a side elevation from the interior of a portion of a car with the improvement applied. 25 Fig. 2 is a plan view of the improved device with the car-frame in section.

The car-frame is represented as a whole at 10, having a doorway-opening defined by the side posts 11 12 and floor 13 of the ordinary form.

30 Disposed adjacent to the side posts 11 12 are clamp-bars 15 16, formed, preferably, in Z shape in cross-section and connected, respectively, by pivoted space link-bars 17, 18, 35 19, and 20 to stop-bars 21 22, attached to the frame 10 and parallel to the posts 11 12 and spaced therefrom, as shown.

The grain-door is represented at 23' of the usual form and overlapping the inner edges 40 of the side posts and overlapped interiorly of the car by the clamp-bars 15 16 when the latter are in their inward positions or when the link-bars are set in their downward positions, as shown in Fig. 1. Then when the link-bars are moved into their upward positions the clamp-bars will be correspondingly moved into their outward positions, which movement will entirely uncover the grain-door and permit its removal bodily, as will be obvious.

45 50 The upper link-bars will preferably be extended into handles 23 24, by which means the clamp-bars may be operated, as will be obvi-

ous. When in their inward positions, the inner edges of the clamp-bars will be in alignment with the inner sides of the post numbers 55 11 12, as shown, so that their presence will not lessen the area of the doorway-opening.

Formed through the clamp-bars 15 16 are spaced slots 25, 26, 27, and 28, curved to correspond with the paths of the bars when operated, and fitting through these slots are pins 29, 30, 31, and 32, connected to the posts 11 12 or other part of the car-frame and provided with lateral heads extending over the clamp-bars adjacent to the slots. By this 65 means the clamp-bars, while left free to be moved by the link-bars, cannot be detached from the car-body. The lower set of slots will preferably be covered by caps 33 34 to prevent the grain from entering the slots and 70 clogging them.

Attached, as by chains 35 36, to the car-body are locking or spacer blocks 37 38, adapted to be inserted into the spaces between the stops and clamp-bars, as shown in Fig. 1, to effectually lock the clamp-bars in their closed positions and prevent accidental displacement. 75 The interiors of the clamp-bars will be serrated, as shown at 39, to increase the "grip" of the bars upon the edges of the door. By 80 this simple means the grain-door is very firmly supported, and all tendency to work loose when subjected to the severe jarring strains incident to grain-cars when in motion and will be found very effective for the purposes described.

The parts may be of any suitable size and of any suitable material, but will preferably be of metal except the door, and the latter may also be of metal; but doors of this character are generally of wood.

Having thus described my invention, what I claim is—

1. The combination with a car-frame having a doorway-opening, of a door having its side edges overlapping and bearing at its outer face upon the sides of the opening, clamp-bars overlapping the edges of the door and bearing upon the inner face thereof, said bars being movable to and from engaging position 95 and provided with guide-slots, bolts extending through the slots for attaching the bars to the frame, links pivoted to the latter and to the bars, pivoted operating-levers engag-

ing the bars, and means for locking the bars in their door-engaging position.

2. The combination of a car-frame having a doorway-opening, a door extending by its side edges over the sides of said opening, clamp-bars connected for lateral movement relative to said opening, stop-bars upon said car-frame parallel to said clamp-bars, and means for operating said clamp-bars, and 10 spacer-blocks adapted for insertion between said stop-bars and clamp-bars, to lock them into engagement with said door, substantially as described.

3. The combination of a car-frame having a doorway-opening, a door extending by its side edges over the sides of said opening, clamp-bars connected for lateral movement

relative to said opening, stop-bars upon said car-frame parallel to said clamp-bars, spaced link-bars movably connected respectively by 20 their ends to said clamp-bars and to said stop-bars, means for operating said clamp-bars, and spacer-blocks adapted for insertion between said stop-bars and clamp-bars, to lock said clamp-bars into engagement with said 25 door, substantially as described.

In testimony that I claim the foregoing as my own I have hereto affixed my signature in the presence of two witnesses.

JOHN WESLEY DAVIS.
